UNITED STATES PATENT OFFICE.

FREDERICK J. KALTEYER, OF PHILADELPHIA, PENNSYLVANIA, ASSIGNOR TO ELECTOSTROP MANUFACTURING COMPANY, A CORPORATION OF PENNSYLVANIA.

HOLDER FOR RAZOR BLADES FOR SHARPENING DEVICES.

Application filed June 24, 1920. Serial No. 391,482.

To all whom it may concern:

Be it known that I, FREDERICK J. KALTEYER, a citizen of the United States, residing in Philadelphia, in the county of Philadelphia and State of Pennsylvania, have invented certain new and useful Improvements in Holders for Razor Blades for Sharpening Devices; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to holders for blades for razor sharpening devices. It has for its object to provide a construction of blade holder embodying novel features for the vertical adjustment of one of the jaws for the purpose of placing the blade in proper position for honing or stropping; also for preventing accidental displacement of the blade from its honing or stropping position; also in the means for gripping the blade in position between the jaws of the holder; also in the construction of the clamping jaws.

To the accomplishment of the foregoing and such other objects as may hereinafter appear the invention consists in features hereinafter described and then sought to be clearly defined by the claims, reference being had to the accompanying drawing forming a part hereof, and in which

Figure 1 is a front view of a portion of a sharpening device illustrated in a general way and having the blade-holder supported therefrom;

Figure 2 is a perspective of the blade-holder;

Figure 3 a vertical section through the holder with a razor blade gripped by its jaws;

Figure 4 is a similar view showing a different adjustment of one of the jaws;

Figure 5, a sectional view, on an enlarged scale, illustrating a three point contact of the jaws with a razor blade.

In the drawing the numeral 1 designates part of a sharpening device having an overhanging arm 2 from which the blade holder

may be suitably supported to sustain the blade between honing or stropping rolls 3. 55

The blade-holder comprises a jaw 4 having inwardly projecting lips 5 to contact with or grip one side of a blade to be sharpened and above which extend spring metal or resilient arms or prongs 6 which will be 60 clamped to the overhanging arm 2 and hold the blade under tension against the honing or stropping roll which bears against one side or the other of the blade. The metal of the blank from which the holder is 65 formed is slotted or cut between the prongs 6 and bent outwardly to form a loop spring 7 and the portion beneath the spring and which forms the second jaw 8 of the holder is bent inwardly at its side edges to form 70 inwardly extending lips 9 one of which is connected to the other by a cross pin 10 to which is connected, preferably pivotally, a threaded bolt 11 which passes through the companion jaw 4 and is provided with a 75 thumb nut 12 which bears against a thimble or sleeve 13 which at its opposite end bears against the jaw so that when the thumb nut is screwed up the jaws are brought towards each other so as to clamp the blade inserted 80 between the two jaws. The upper end of jaw 8 is formed with an inwardly extending lip 14, which may be made by slitting the middle portion of the loop spring and bending it inwardly as illustrated, and the 85 lower end of the jaw is also formed with an inwardly extending lip 15. Both of the lips 14 and 15 are apertured for the passage of an adjusting stem or bolt 16, the upper portion of which is threaded for engagement with threads in an aperture of the loop 7. This stem or bolt 16 constitutes, 90 practically, a component part of the jaw 8 and therewith acts in conjunction with the companion jaw to clamp a blade between 95 the two jaws. The lower end of the stem or bolt 16 is formed with a groove 17 and the inwardly extending lips 5 of jaw 4 are formed each with a groove 18, which grooves are designed to receive the opposite edges 100 of the back of an old style razor blade 19 and afford a better grip of the jaws on a blade of that type. The lips 5 bearing against one side of the razor blade and the stem or bolt 16 bearing against the other 105 and at a point intermediate of the bearing

points of the lips 5 a three point gripping contact of the jaws with the blade is afforded and this tends to create or effect a better gripping action on the blade and 5 guard against accidental slipping of the blade in the operation of honing or stropping. The purpose of providing for a vertical adjustment of the stem or bolt 16, or practically of one of the clamping jaws is 10 this. It frequently happens that the back of an old style razor blade will project more from one side than the other or that the two sides are not exactly alike. When such is 15 the case and the clamping action of the jaws is exerted on the blade, the blade will be deflected so as to stand obliquely to one side or the other of a vertical line as illustrated in Figures 3 and 4, whereas the blade should stand true to a vertical for the proper action 20 of the honing or stropping rolls on the blade. This is overcome by a vertical adjustment, up or down as necessary, of one of the clamping jaws so as to tilt the blade sufficiently to bring it to a vertical position 25 as illustrated in Figure 1 of the drawing. In the present embodiment of the invention this is effected by screwing the stem or bolt 16 up or down as may be necessary for the proper adjustment. To provide against ac- 30 cidental change in adjustment of the stem or bolt 16 incidental to operation of the sharpening machine, the stem or bolt is serrated or knurled as indicated at 19 and a portion of the jaw 8 is slotted and pressed 35 inward to form a lip 20 which will press against the knurled portion of the stem or bolt and serve as a lock against accidental turning of the stem or bolt.

I have described with particularity the 40 preferred details of the various parts but changes can be made therein and essential features of the invention be retained.

Having described my invention and set forth its merits what I claim is:

45 1. A blade holder for sharpening devices comprising oppositely disposed jaws, one of the jaws having bearing contacts for one

side of a blade, and a stem associated with one jaw to constitute a bearing contact for the other side of the blade and adjustable 50 lengthwise of the jaw for adjustment of a blade.

2. A blade holder for sharpening devices comprising oppositely disposed jaws, one of the jaws having grooved bearing contacts for one side of a blade, and a stem associated with one jaw and having at its end a grooved bearing contact for the other side of the blade and adjustable lengthwise of the jaw for adjustment of a blade. 60

3. A blade holder for sharpening devices comprising oppositely disposed jaws, one of the jaws having at its sides inwardly extending bearing contacts for one side of a blade, and a stem associated with the other jaw and positioned intermediate of the bearing contacts of the companion jaw and constituting a bearing contact for the other side of the blade. 65

4. A blade holder for sharpening devices comprising oppositely disposed jaws, one of the jaws having bearing contacts for one side of a blade, spaced-apart lips extending inwardly from the other jaw, and a stem passed through said lips and one end constituting a bearing contact for the other side of the blade. 70

5. A blade holder for sharpening devices comprising oppositely disposed jaws, one of the jaws having inwardly extending bearing contacts for one side of a blade and upwardly extending supporting prongs, the other jaw having a loop support from its companion jaw and formed with inwardly extending spaced-apart lips, and an adjusting stem passed through said lips and one end constituting a bearing contact for the other side of the blade. 75 80 85

In testimony whereof I affix my signature in presence of two witnesses.

FREDERICK J. KALTEYER.
